UNITED STATES PATENT OFFICE.

JOHN E. GALLANT, OF BOSTON, MASSACHUSETTS.

CURRENT-RECTIFYING APPARATUS.

1,290,167.

Specification of Letters Patent. Patented Jan. 7, 1919.

Application filed May 29, 1917. Serial No. 171,795.

To all whom it may concern:

Be it known that I, JOHN E. GALLANT, a citizen of the United States, residing at Boston, in the county of Suffolk and State of Massachusetts, have invented a new and useful Current-Rectifying Apparatus, of which the following is a specification.

This invention relates to current rectifying apparatus of the general type shown in in 10 my prior application Serial No. 141,020 filed by me January 6, 1917.

In this prior application I disclosed a form of rectifying apparatus in which the circuit changes were produced by the joint action 15 of intermeshing spiral gears, each gear being formed of insulating and conducting toothed disks joined together in a rigid structure.

It is the general object of my invention to improve the construction and operation of 20 these gears by providing for slight relative angular movement between the insulating and conducting portions of one of the gears. By such provision I obtain the important advantages hereinafter described.

25 It is also an object of my invention to provide a device which shall materially reduce or entirely prevent sparking in the rectifying apparatus when the current is broken or reversed. A further feature of my invention 30 relates to the provision in a rectifying apparatus of connections so designed that the charging rate in different sections of the battery will be inversely proportioned to the voltage therein.

35 My invention further relates to certain arrangements and combinations of parts which will be hereinafter described and more particularly pointed out in the appended claims.

A preferred form of my invention and a 40 modification thereof are shown in the drawings, in which—

Figure 1 is an elevation, partly in section, of the preferred form of my apparatus, this figure also showing the connections and use 45 of the apparatus diagrammatically.

Figs. 2, 3 and 4 are enlarged views showing the successive contacts made by the teeth of the intermeshing spiral gears, as their relative position changes;

50 Fig. 5 is a partial sectional view of one of the gears, taken along the line 5—5 in Fig. 6;

Fig. 6 is a sectional plan view, taken along the line 6—6 in Fig. 5;

55 Fig. 7 is a view similar to Fig. 1, but

showing a modified form of my invention, and

Figs. 8, 9 and 10, are enlarged views showing the successive contacts made in the operation of the modification shown in 60 Fig. 7.

Referring to Figs. 1 to 6, the preferred form of my invention comprises a pair of intermeshing spiral gears 10 and 20, the gear 10 being preferably the driving gear. 65 These spiral gears 10 and 20 are each formed of several sections of conducting and insulating materials.

The gear 10 comprises a central disk 11 of vulcanized fiber or some similar insulating material, secured to or integral with a hub 12, rotatable in suitable bearings 13. Two conducting or metal disks 14 and 15 are loosely mounted upon the hub 12 and are confined from axial movement by two in- 75 insulating flanges or disks 16 and 17.

Short shafts 30 and 31 are fixed in the hub 12, but are separated at their inner ends by a portion of the insulating material of which the hub 12 and disk 11 are formed. 80 Pins 32 of conducting material extend outward from the shafts 30 and 31 into position to support the metal gears 14 and 15. The gears 14 and 15 are each provided with an arc-shaped slot 18 through which extends a pin 19^a fixed in one of the disks 16 or 17. Springs 19 (Fig. 5) are mounted in the slots 18, and yieldingly force the metal disks backward until the front end of each slot 18 engages a stop pin 19^a. 90

Gear teeth are cut in the edges of all the disks but the teeth of the gears 14 and 15 are preferably formed somewhat thinner than the teeth of the fiber disks 11, 16 and 17. Consequently as the gears are forced 95 backward by the springs 19, they engage the teeth of the intermeshing gear 20 with their rear faces only.

The gear 20 is preferably formed of a single metal disk 21, secured between fiber or 100 insulating disks 22 and 23 (Fig. 3) these parts being secured together to form a single rigid structure.

Brushes 33 and 34 engage the ends of the shafts 30 and 31 respectively, and are connected by wires 35 and 36 in the opposite poles of a storage battery B. The disk 21 is connected through its shaft 24 and brush 25 to the ground at G. A magneto or other form of generator M is connected by a wire 110

37 to the middle point of the battery and the other pole of the magneto is grounded at G'. A high resistance R is also shunted between terminals of the magneto M, as indicated in Fig. 1.

Having described the construction of the preferred form of my invention I will now describe the operation of the device, in changing the circuit through the rectifier 10 from the magneto or generator to the battery.

The disk 21 in the gear 20 is continuously connected through the ground connection to one side of the generator M; the disk 14 15 of the gear 10 is continuously connected through the wire 35 to the negative side of the battery B; and the disk 15 of the gear 10 is continuously connected through the wire 36 to the positive side of the battery B. Also the intermediate or middle point in the battery is continuously connected to the second pole of the generator M. As the gears 10 and 20 revolve in timed relation to the pole changes or alternations of the generator M, the circuits are continuously reversed so that the alternating current of the generator will be delivered to the battery as a pulsating direct current.

In Fig. 2 I have shown the tooth 21^b of the disk 21 in engagement with the tooth 15^a of the disk 15, thus completing a circuit to the positive pole of the battery. At the same time it will be noted that the disk 14 is moved backward by its spring 19 so that it does not engage the rear face of the tooth 21^a of the disk 21. In Fig. 3 the tooth 21^b has moved forward until it engages the tooth 11^a of the fiber disk 11, thus breaking the circuit from the generator to the battery. In Fig. 4 the tooth 21^b has moved still farther forward, and now engages the rear face of the tooth 14^a in the metal disk 14, thus completing a circuit through the wire 35 to the negative side of the battery. As 45 the gear continues to revolve a tooth 21^c of the disk 21 will move forward and engage the tooth 15^b of the disk 15, the circuits thus being restored to their first position.

The resistance R is provided to reduce 50 or prevent sparking in the rectifying apparatus when the contact between the disks is broken. The connection of the generator to the middle point of the battery by the wire 37 permits charges to be sent first into one half of the battery and then into the other, as the direction of current is reversed. This connection 37 also tends to equalize the charge in the different parts of the battery as that portion of the battery which is 55 of lower voltage will naturally be charged more rapidly than the portion which is of higher voltage.

In Figs. 7 to 10 I have shown a modified form of my construction in which intermeshing spiral gears 40 and 50 are used.

The gear 40 is similar to the gear 10 previously described, and is composed of a single loosely mounted metal disk 41, electrically connected to a shaft 42, extending through the insulating hubs 43 and 44. The disk 41 70 is inclosed by insulating or fiber disks 45 and 46. The spring connection between the disk 41 and the disks 45 and 46 is similar to those used in the preferred form and fully shown in Figs. 5 and 6. The gear 50 is 75 identical with the gear 20, and comprises a metal disk 51, secured between insulating or fiber disks 52 and 53 (Fig. 8). The gears 40 and 50 are connected to rotate in timed relation to the alternations of the generator M.

The successive circuit changes are shown diagrammatically in Figs. 8, 9 and 10. In Fig. 8 the tooth 51^a of the gear 51 is in engagement with the rear face of the tooth 41^a 85 of the movably mounted gear 41. As the parts move forward, the teeth 41^a and 51^a move out of engagement as shown in Fig. 9, but the yielding mounting of the gear 41 causes the teeth to move backward, so that 90 the tooth 41^b cannot engage the rear face of the tooth 51^a. This condition is more clearly illustrated in Fig. 10, in which the teeth are moved forward still farther in their relative position.

It will thus be clear that the teeth are in engagement successively for a certain length of time, and that they are then out of engagement for a corresponding length of time. The parts are so timed that the gears 10 engage during the other half of each alternation. Thus only one half of the output of the generator is conducted to the battery, the current being an intermittent direct current rather than a substantially continuous 10 pulsating direct current as in the preferred form of my apparatus. This form of my invention is desirable when it is not necessary to utilize the entire output of the generator, and when simplicity of parts is 11 greatly desired.

It will be evident by reference to the drawings that whenever a tooth of the movable metal disk engages a tooth in the co-operating gear, an obtuse angle of the movable tooth first engages the tooth surface of the other gear, whereby the movable tooth is readily pushed forward into working position against the pressure of its spring 19.

Having thus described my invention, it 12 will be evident that changes and modifications can be made therein, by those skilled in the art, without departing from the spirit and scope of my invention as set forth in the claims, and I do not wish to be otherwise limited to the details herein disclosed, but what I do claim is:

1. A current rectifying apparatus comprising intermeshing spiral gears, one gear having a conducting toothed disk fixed be- 13

- tween two insulating toothed disks, and the second gear having a conducting toothed disk mounted for slight angular movement between two insulating toothed disks.
5. 2. A current rectifying apparatus comprising intermeshing spiral gears, one gear having a conducting toothed disk fixed between two insulating toothed disks, and the second gear having a pair of conducting toothed disks separated and inclosed by insulating toothed disks, each conducting disk having a slight angular movement relative to the insulating disks and independent of each other.
10. 3. A current rectifying apparatus comprising intermeshing spiral gears, one gear having a conducting toothed disk fixed between two insulating toothed disks, and the second gear having a pair of conducting toothed disks separated and inclosed by insulating toothed disks, each conducting disk having a slight angular movement relative to the insulating disks and independent of each other, and means to force said movable disks yieldingly in one direction.
15. 4. A current rectifying apparatus comprising intermeshing spiral gears, one gear having a toothed metal disk rigidly mounted between toothed fiber disks, and the second gear comprising a toothed metal disk movably mounted between two fiber disks, a stop to limit the relative movement of said metal disk, and a spring mounted in said
20. second gear effective to yieldingly retain said movable metal disk at its limit of movement in one direction.
25. 5. In a current rectifying apparatus, a spiral gear comprising a pair of toothed metal disks each electrically connected to a short shaft, said shafts being insulated from each other, and said disks being spaced apart between toothed fiber disks rotatable with said shafts, said metal disks having limited angular movement relative to said shafts and to said fiber disks.
30. 6. A current rectifying apparatus comprising intermeshing spiral gears, each of said gears having conducting and non-conducting toothed portions, and the conducting portion of one gear being movably mounted relatively to the non-conducting portion.
35. 7. A current rectifying apparatus comprising intermeshing spiral gears, each of said gears having conducting and non-conducting toothed portions, and the conducting portion of one gear being movably mounted relatively to the non-conducting portion, and means to force said movable conducting portion yieldingly rearward, whereby an obtuse angle of each movably mounted tooth first engages a tooth of the coöperating gear.
40. In testimony whereof I have hereunto affixed my signature.
45. JOHN E. GALLANT.
